SPECIFICATION forming part of Design No. 13,521, dated January 16, 1883.

Application filed November 22, 1882. Term of patent 7 years.

To all whom it may concern:

Be it known that I, HENRY R. BROWN, a citizen of the United States, residing at Greeneville, in the county of Greene and State of Tennessee, have invented and produced a new and original Design for Show-Cases, of which the following is a specification.

In the accompanying drawings, forming part of this specification, Figure 1 is a perspective view from the front and one end of the show-case, and Fig. 2 is a similar view from the rear and one end. Fig. 3 is a cross-section and elevation. These figures are deemed necessary and sufficient to fully illustrate my design, and in all like letters of reference, wherever they occur, indicate corresponding parts.

My design has reference to portable show-cases, such as may be employed upon counters and tables, or upon the tops of other show-cases, and on brackets for the display of samples of light goods, such as medicines, jewelry, spools, and other small articles, the object of the design being to produce an ornamental show-case of light and attractive appearance, having a rounded or curved transparent front, open-work segmental or bracket shaped end pieces, with provision for advertising sign-plates, and an ornamental sign-plate above the front and connected with the bracket-shaped end pieces, all of which will be herein-after first fully described, and then pointed out in the claims.

Heretofore show-cases for the small samples of druggists' sundries and the like have been made heavy, not only in fact, but in appearance, and fail to afford attractive and convenient spaces for the display of advertising sign-plates without detracting from the general form and ornamental effects of the show-case itself.

In my design the end plates, A A, are made in the general shape of a quarter of a circle, the front edges curving to conform to the shape of the transparent front B, each having a slight upward projection, a, made ornamental and joined with the projecting top plate, C, and each provided at the base with another ornamental projection, b, which joins with the ends of the front molding, D. The end plates are of open-work, as plainly shown, preferably having radial arms, as at c e, and giving to the ends or brackets and to the general struct-

ure a light and pleasing appearance. On each end plate, and concentric with the exterior curve thereof, are the sign-plates, as at d d, intended to bear any desired sign-card, and forming a curved panel, which adds to the finish of the end plates. Below the lower margins of these panels (which are solid) the open-work of the end plates affords a comparatively unobstructed view, giving to the whole structure a light and graceful appearance. The front molding, D, extends between the end plates and projects out far enough to afford the appearance of a finished solid base in front. The top plate, C, also extends between the end plates and finishes the top of the structure. This top should not appear heavy, and for that reason I remove the material which would otherwise form the spaces between the letters of the sign-card, admitting the light therethrough and rendering the sign-plate an ornamental finished top, light and attractive in appearance.

The back part of the show-case is open, the tray being curved to conform to the curve of the transparent front, and placed close to the front, so as to bring the articles displayed in position where they can always be viewed to best advantage.

Of course it will be understood that the sign-plates may bear any desired sign.

The details of ornamenting the open-work end plates might also be changed without departing from my invention.

The dotted lines in Fig. 1 represent articles within the case, (the case being only partly filled.)

The design as above described may be made up in any desired size and the plates colored to suit the fancy.

The show-case alone makes a neat ornament for the counter or shelf, and contributes to the attractiveness of the goods displayed therein.

Having now fully described my invention, what I claim as new, and desire to secure by Letters Patent, is—

1. In a design for show-cases of the character herein set forth, the ornamental open-work end plates provided with the sign-panels curved to correspond with the front edges of said plates, and located and arranged substantially as shown and described.

2. In a design for show-cases, wherein the ends are made of ornamental open-work, and

the front curved as explained, the projecting top open-work sign-panel extending from end to end, and arranged substantially as shown and described.

5 3. The herein-described design for showcases, the same consisting of the curved front, the quadrant-shaped ornamental end pieces of open-work, as explained, the end and top sign-

panels, and the bottom molding, all combined and arranged substantially as shown and described.

HENRY R. BROWN.
